UNITED STATES PATENT OFFICE.

SIMON W. WARDWELL, OF PROVIDENCE, RHODE ISLAND, ASSIGNOR TO SUPREME KNITTING BOBBIN COMPANY, OF PORTLAND, MAINE, A CORPORATION OF MAINE.

WINDING-MACHINE.

1,118,604.

Specification of Letters Patent. Patented Nov. 24, 1914.

Application filed September 4, 1908. Serial No. 451,701.

To all whom it may concern:

Be it known that I, SIMON W. WARDWELL, a citizen of the United States, residing at Providence, in the county of Providence and State of Rhode Island, have invented certain new and useful Improvements in Winding-Machines, of which the following is a specification.

My invention relates to winding machines for winding bobbins or yarn packages of cylindrical body, taper nose and substantially flat base, in which the yarn is laid with a foundation cone consisting of superimposed layers having gradually increasing lengths of traverse.

My invention consists particularly of devices for use in connection with the traverse-regulating mechanism of a winding machine similar to that shown and described in my pending application, Serial No. 451,700 filed Sept. 4, 1908.

The accompanying drawings illustrate, respectively: Figure 1, a front elevation of the device applied to the traverse-regulating mechanism above referred to; Fig. 2, an end view of the same.

Referring to the drawings, 5 is the traverse cam, which, through suitable connections, imparts reciprocation to the yarn depositing guide, not here shown, that lays the yarn on its holder. These connections consist of the lever 12, pivoted on the fulcrum stud 11, with its lower arm extending downward into proximity with the cam 5 and bearing a roll 13 on the stud 10, the former engaging the groove 6 of the cam. The stud 11 is secured in the frame of the machine and is formed at its outer end with a peripheral groove, into which is sprung a spring-ring or clip 40, which bears against a washer 41, which, in turn, bears against the end of the hub 42 of the lever 12 to retain the latter in position on its bearing.

The upwardly extending curved arm of the lever 12 has a slot 14, on one side of which are formed the rack teeth 15. Fitted to the slot 14 and adapted to mesh with the teeth 15 is a pinion 20, which carries a ratchet wheel 23 and is rotatably secured to one end of a connecting-rod 19. The latter serves as a link between the lever 12 and the traverse-rod 16, which carries the yarn-depositing guide, not here shown, but fully

illustrated and described in my pending application before referred to. With the pinion 20 in its lowermost position in the slot 14, as shown by full lines in Fig. 1, the oscillation of the lever 12 will cause a relatively short reciprocation of the traverse-rod 16, owing to the disparity in leverage between the two arms of the lever; but by raising the connecting-rod's point of connection with the upper arm of the lever 12, it is obvious that the leverage on the connecting-rod 19 will be increased and the traverse of the rod 16 correspondingly augmented.

The object of increasing the traverse of the rod 16 is to cause the thread-guide carried thereby to deposit the yarn in layers of gradually increasing length, as heretofore explained, and this action is secured through instrumentalities, which are acted upon by the yarn as it is laid on the holder in a conical mass of gradually increasing diameter.

By rotating the pinion 20 in the direction indicated by the arrow in Fig. 1, the pinion is caused to travel upward on the arm of the lever 12. This rotation is automatically effected through the means of a pawl 22, which has a finger 21 adapted to engage the teeth of the ratchet-wheel 23 each time the lever 12 oscillates toward the right into the position shown by dash lines in Fig. 1.

The pawl 22 is pivoted on a pin or stud 24 and is adapted to swing to carry the finger 21 upward as the wheel 23 travels up on the lever 12. To prevent the pawl 22 from being accidentally moved up out of range of engagement with the teeth on the wheel 23, a guard 75 is provided, which preferably takes the form of a curved extension of the pawl 22. As here shown, the pawl 22 is made of sheet metal, bent in angle form to give it the required stiffness and having a U-shaped extension 22^a, which gives a double bearing on the stud 24. A bushing 22^b extends through the two legs of the extension 22^a and the finger 21 is fastened on the top of the pawl by riveting or any other suitable method.

The means for effecting the automatic adjustment of the pawl 22 to cause it to follow the upward movement of the pinion 20, so that it may at all times be opposed to

the teeth of the wheel 23, consists of a lever A, which carries at one end of its arm 26 the contact wheel 25. The wheel 25 is adapted to bear on the surface of the yarn mass as the foundation cone is built up of superimposed layers and as the mass increases in diameter, the wheel 25 is moved out, away from the winding spindle. In Fig. 2, the full lines represent the position 10 of the lever A at the start of the winding, with the wheel 25 bearing against the tube on which the package is wound, represented by the dash line circle a. The dash lines B represent the lever at the completion of the 15 winding when the base of the cop has grown to the diameter represented by dash lines b.

The means for connecting the lever A to control the movement of the pawl 22 will now be particularly described and the distinguishing feature of the present invention comprises an arrangement for automatically disengaging this means when the cop reaches its predetermined size at the base, so that the pawl 22 is relieved from 25 further engagement with the wheel 23 and returned to its initial position.

At the end of the arm 29 of the lever A is a ball 30 formed with a shank 31, which is riveted or screwed into the right-angle portion 29^a. A corresponding ball 32 is connected with the pawl 22. The lever A is made of sheet metal, as are practically all of the parts of the present structure, to make them relatively light, so that there will be 35 no undue resistance to the movement of the mechanism from the wheel 25, which presses on the cop. If the parts were of any considerable weight, an extreme resistance to the movement of the wheel 25 would cause 40 the latter to sink into the comparatively soft yarn mass and the shape of the package would become irregular and the yarn might be injured.

Connecting the lever A with the pawl 22 is 45 a link 34 consisting of two halves formed of sheet metal of trough-shaped section to provide for stiffness, and having spoon-shaped sockets at each end to receive the balls 30 and 32. Midway between the extremities of the 50 halves, are formed two concave indentations 34^a-34^b, adapted to receive the ends of a spring ring 35, which serves as a clip to hold the two parts of the link 34 together and provide a yielding friction on the balls 30 and 32. The link 34 gives a positive connection 55 between the operating parts, with universal joints at each end, which provide for a smooth movement without play or backlash. It will also be noticed that the parts 60 are extremely light, yet so formed as to give the necessary rigidity.

In the invention of my application previously referred to, the connection between the lever A and pawl 22 is positive, with no provision for disengagement, but in the im-

proved device now shown, I provide means for releasing the pawl 22 from the lever A after it has been carried to its extreme upward position, so that it will not continue to engage the ratchet-wheel 23.

In my previous invention the ball 32 is mounted on the pawl 22, but in the present device, I employ an intermediary connection which consists of an auxiliary lever 43 to carry the ball. The lever 43 is preferably formed of sheet metal with a disk-shaped counterweight 44 at one end and bent double at the opposite extremity at 45, in U-form, to provide a bearing on the stud 24. Referring to Fig. 2, the drawing shows a bushing 46 secured in the two extensions of the bent portion 45, similar to the manner in which the bushing 22^b is fastened in the pawl 22. The bushing 46 gives a longer bearing on the stud 24, and abutting its outer end is a wire clip 47 sprung into a peripheral groove on the stud 24 and serving to hold the lever 43 and pawl 22 in place on their bearings.

The portion 45 of the lever 43 extends parallel to the main arm for some distance and takes the form of a quadrant 48 with two arms 49 and 50 extending from the bushing 46. The ball 32 has a shank 32^a which extends through an ear 51 on the front of the lever 43 and is riveted into the lower end of the quadrant 48, to provide a strut between the two portions of the lever. Pivoted on the bushing 46 is an arm 52, the upper end of which is bent over the edge of the quadrant 48 to form a stop 53. The arm 52 is provided with a slot 54 through which extends a screw 55, screwed into the arm 49 of the quadrant. The slot 54 allows the stop 53 to be adjusted around the quadrant, with certain limits, and by tightening the screw 55, the arm 52 is fastened in its adjusted position.

Pivoted on the pawl 22 at 56 is a latch 57 having one end 58 formed with a catch or 110 detent 59, adapted to ride up over and engage the stop 53. The opposite end 60 serves as a trigger to raise the catch 59 and free it from the stop 53. The trigger 60 is engaged by a pin 61 when the pawl 22 reaches its 115 extreme upward position. The pin 61 is preferably attached to, or formed on, a member 62 which swivels on a screw 63 so that by loosening the screw the pin can be adjusted to regulate the point of knock-off of 120 the latch 57.

It will be noticed that while in my previous invention, the lever A was formed of two parts, adjustable in relation to each other, in the present invention the lever A is of one piece. The adjustment between the relative positions of the wheel 25 and pawl 22 is now effected through the adjustment of the arm 52. It is evident that by moving the stop 53 around the quadrant 48 to the right, the 130

pawl 22 will be raised in relation to the position of the wheel 25, and vice versa when the stop is moved in the opposite direction.

The operation of my device is as follows:

- 5 The parts are set with the pawl 22 in its lowermost position bearing on the hub 42 of the lever 12 and the pinion 20 at the bottom of the slot 14. The wheel 25 is set against the tube on which the winding is to 10 be performed, indicated by dash lines *a*—Fig. 2, and the stop 53 adjusted so that it will engage the catch or detent 59. The rotation of the cam 5 causes the lever 12 to oscillate and the wheel 23 is carried over to 15 bring its teeth into contact with the finger 21. The engagement of the finger 21 with the wheel 23 causes the latter to rotate and the pinion 20 travels up on the teeth 15 toward the top of the lever 12. Meanwhile, 20 the rod 16 is caused to reciprocate, through the connecting-rod 19, and the thread-guide carried thereby is traversed back and forth along the winding spindle to lay the yarn in gradually increasing lengths of layers. As 25 the yarn builds up on its tube or holder, it bears against the wheel 25, causing the latter to move downward, thereby raising the arm 29 of the lever A, and through the connection 34, carrying the lever 43 upward. The 30 engagement of the stop 53 with the catch of the latch 57 acts to raise the pawl 22 synchronously with the movement of the lever 43 and the finger 21 follows the wheel 23 to continue to impart to the latter an intermittent 35 rotation. When the pinion 20 has reached a point on the lever 12 to give the predetermined maximum traverse to the thread guide, the trigger 60 comes into contact with the pin 61 and the further movement 40 of the pawl 22 causes the latch 57 to be raised, as shown by the dash lines in Fig. 1, to release it from the stop 53. This allows the pawl 22 to drop back, under the influence of gravity, to its initial position and 45 the wheel 23 receives no further impulse to rotation, so that during the remainder of the operation of the machine, the traverse of the thread guide remains constant. As explained in my previously filed application, 50 the wheel 23 is held against the face of the lever 12 by a spring 74, which gives a frictional contact sufficient to prevent the pinion 20 from moving back from the position to which it has been advanced.
- 55 When the package is completed and removed from the winding spindle, to prepare for winding a new bobbin, it is only necessary to turn the wheel 23 backward by hand to bring the pinion 20 to its lowermost position; and to set the wheel 25 against the tube on which the bobbin is to be wound.
- 60 While I have shown the preferred form and arrangement of the parts, it will be understood that modifications might be made

in the structure without departing from the scope of my invention; therefore, I do not limit myself to the precise arrangement shown and described, but

What I claim is:—

1. In a winding machine, the combination with a traverse-bar, of a lever to reciprocate the bar, means to oscillate the lever, a link between the traverse-bar and the lever, variable as to its point of connection 70 on the lever, a wheel mounted on said link and acting to vary the point of connection, means to actuate the wheel during the winding, and automatic devices to arrest the operation of said means at a predetermined 75 point in the winding.

2. In a winding machine, the combination with a traverse-bar, of an oscillating lever having a slot, means to oscillate the lever, a connection between the traverse-bar and 80 the lever, engaging the latter by its slot, means controlled by the growth of the package to shift the connection in said slot, and automatic devices to render said means inoperative at a predetermined point in the 85 winding.

3. In a winding machine, the combination with a traverse-bar, of an oscillating lever having teeth, a connection between the traverse-bar and the lever, a pinion on the connection engaging the teeth of the lever, a wheel to turn the pinion, means to turn the wheel, and automatic devices to cause said means to become inoperative at a predetermined point in the winding. 95

4. In a winding machine, the combination with a traverse-bar, of an oscillating lever having teeth, a connection between the traverse-bar and the lever, a pinion on the connection engaging the teeth of the lever, a wheel to turn the pinion to shift the connection on the lever, a pawl to engage the wheel, means to automatically vary the position of the pawl coördinately with the shifting of the wheel with the connection, 105 and means acting automatically to disconnect said means from the pawl and allow the latter to return to its initial position.

5. In a winding machine, the combination with a traverse-bar, of an oscillating lever, 115 means to oscillate the lever, a connection between the traverse-bar and the lever, shiftable thereon, means to shift the connection on the lever, actuated by the increase in size of the package wound, and automatic devices to discontinue the operation of said means when the package reaches a predetermined diameter.

6. In a winding machine, the combination with a traverse-bar, of an oscillating lever, 125 means to actuate the lever, a connection between the traverse-bar and the lever, shiftable on the latter by the growth of the package wound, and automatic devices to prevent further shifting of the connection when 130

the package reaches a predetermined diameter.

7. In a winding machine, the combination with a guide-carrying traverse-bar, of a cam having a single extent of traverse, means to connect the cam to reciprocate the traverse-bar, independent means to extend the range of action of the cam to gradually augment the length of traverse of the bar during the winding, means operated by the growth of the package wound to actuate said cam extension means, and devices adapted to act automatically to discontinue the operation of the package controlled means at a predetermined point in the winding.

8. In a winding machine, the combination with a traverse-bar, of a cam of single traverse to reciprocate the bar, means intermediate the cam and the traverse-bar operated independently of the cam to vary the operative effect of the latter, means controlled by the diameter of the yarn mass being wound to actuate said intermediary means to augment the extent of traverse of the bar, and devices to discontinue the operation of said means when the yarn mass reaches a predetermined diameter.

9. In a winding machine, the combination with a traverse-bar, of an oscillating lever to traverse said bar, a connection between the bar and the lever, adapted to be shifted on the lever to vary the traverse of the bar, means to shift said connection, a contact member engaged by the yarn mass being wound to operate said means, and devices connecting the contact member with the shifting means and adapted to be automatically released when the contact member reaches a predetermined position.

10. In a winding machine, the combination with a traverse-bar, of means for reciprocating the bar, devices for varying the extent of reciprocation, a member to actuate said devices, a contact member adapted to bear on the winding, means to connect the contact member with the actuating member, and adjustable means to release the connecting means automatically at a predetermined point in the winding.

11. In a winding machine, the combination with a traverse-bar, of means for reciprocating the bar, devices to vary the extent of reciprocation, a member movable to actuate said devices, a contact member to move said member, and a latch on one of said members adapted to engage the other and arranged to be released automatically when the contact member reaches a predetermined position.

12. In a winding machine, the combination with a traverse-bar, of means to reciprocate the bar, devices to vary the extent of reciprocation, a member 22 to actuate said devices, a contact member operated by the

yarn mass being wound, a lever 43 connected to be moved by the contact member, a latch on the member 22, adapted to engage the lever 43, and means to automatically disengage the latch to release the member 22 when the contact member reaches a predetermined position.

13. In a winding machine, the combination with a reciprocating traverse-bar and means to vary the extent of reciprocation of the bar, of a pivoted member 22 adapted to be moved to actuate said means, a lever 43, a contact member 25 connected to move the lever 43, and a latch on the member 22 adapted to engage the lever 43.

14. In a traverse-regulating device for winding machines, the combination with a contact member 25 adapted to be moved by the pressure of the growing cop, a lever 43 connected with said contact member, a member 22 to actuate the traverse-regulating mechanism, and means to connect the member 22 with the lever 43, said means adapted to be automatically released when the contact member reaches a predetermined position.

15. In a traverse-regulating device for a winding machine, the combination with a contact wheel 25, and a lever A carrying said wheel, of a second lever 43 pivoted at 24 and formed with a quadrant 48, a stop 53, adjustable around the quadrant, a connection 34 between the levers A and 43, a pawl 22, also pivoted at 24, and a latch 57 on the pawl 22, adapted to ride on the quadrant and engage the stop 53.

16. In a traverse-regulating device for winding machines, the combination with a lever A, of a second lever 43, a connection 34 between the two levers, a pawl 22, a latch on said pawl adapted to engage the lever 43, and an adjustable member 61 adapted to engage the latch to release it from the lever 43 when the pawl reaches a predetermined position.

17. In a traverse-regulating device for winding machines, the combination with a lever 43 pivoted at 24 and adapted to be moved during the winding, and formed with a quadrant 48, a stop 53 swiveled to move around the quadrant, means to adjust the stop on the quadrant, a pawl 22 fulcrumed at 24, a latch 57 pivoted on the pawl 22 and formed with a detent to engage the stop 53, and with a trigger 60 at its opposite end, and means to engage the trigger to release the latch after the pawl 22 reaches a predetermined position.

18. In a traverse-regulating device for winding machines, the combination with a lever 43 formed of sheet metal bent back at one end in a U-shaped portion formed with a quadrant 48 and having a bearing extending through the parallel sides, of a stop 53 having an arm pivoted on the bear-

ing and formed with a slot, and a screw extending through the slot and screwed into the quadrant.

19. In a traverse-regulating device for winding machines, the combination with an oscillating lever 12, of a connecting rod 19 having a connection on the lever, means to shift the connection along the lever, including a wheel 23, a pawl to rotate the wheel, and means to move the pawl to follow the wheel, comprising a contact wheel 25 moved by the yarn mass, a lever A carrying said wheel, a second lever 43 connected therewith, a latch 57 on the pawl, and means adjustable on the lever 43 to engage said latch to move the pawl from the lever.

20. In a traverse-regulating device for winding machines, the combination with

an oscillating lever 12, of a connecting-rod 19 having a connection on the lever, means to shift the connection along the lever, a ratchet-wheel to operate said means, a pawl 22 fulcrumed at 24 and adapted to engage the teeth of the ratchet, a lever 43 also fulcrumed at 24, a latch 57 adapted to engage the pawl 22 with the lever 43, a lever A connected at one end with the lever 43, and a contact wheel 25 at the opposite end of the lever A adapted to bear on the surface of the yarn mass being wound.

In testimony whereof I affix my signature in presence of two witnesses.

SIMON W. WARDWELL.
